(57) **CLAIM**

The ornamental design for a mirror, as shown and described.

DESCRIPTION

FIG. 1 is a perspective view of the mirror.

FIG. 2 is a left side elevational view of the mirror with the right side, top and bottom elevational views being a mirror reflection of the left side elevational view.

FIG. 3 is a front elevational view of the mirror.

FIG. 4 is a rear elevational view of the mirror.

FIG. 5 is a perspective view of the mirror including a hanging assembly on the back thereof; and,

FIG. 6 is a cross sectional view of a section of the mirror perimeter taken along line 6—6 of FIG. 2.
